UNITED STATES PATENT OFFICE.

HENRY H. HARADA, OF EAU GALLIE, FLORIDA.

ELECTRICALLY-OPERATED DIRECTION SIGNAL.

Application filed June 17, 1926. Serial No. 116,611.

This invention relates to improvements in electrically operated direction signals which are adapted for use particularly on motor vehicles and the like, in order to indicate the 5 direction of movement thereof.

An object of this invention resides in providing a direction signal for motor vehicles having a movable signal arm adapted to be placed in any one of a plurality of predetermined 10 positions and which normally retains one of said positions in which suitable operating means is provided for moving said arm operable electrically through the operation of a remote control device placed in convenient 15 reach of the operator of the motor vehicle.

A further object of the invention is to provide a specially constructed operating mechanism for a signal arm of direct signals having 20 electro-magnetic means energizable to operate the signal arm for signalling purpose with which is associated suitable latching means adapted to normally retain the signal arm in a set position and which is operable 25 in a predetermined manner by the operation of the electro-magnetic means to permit the operation of said signal arm.

The invention further comprehends the provision of a special mounting structure for 30 the electro-magnetic mechanism while as the structure for rotatably supporting the signal arm in order that it may be assembled or removed from a protective casing without requiring the disassemblage of the operative 35 parts of the mechanism and for this purpose a special mounting member is provided and formed of a single piece of stamped sheet material in such a way as to form supporting extensions for the operative parts of the apparatus.

The invention comprehends numerous other objects residing in the details of construction and arrangement as well as size and shape of the parts which are more particularly pointed out in the following description and claims directed to the preferred form of the invention, it being understood, however, that various changes may be made in the size, shape and arrangement 45 of these parts without departing from the spirit or scope of the invention as herein set forth.

In the drawings forming part of this application:

Figure 1 illustrates a rear elevational view of the improved direction signal.

Fig. 2 is a view of the electromagnetic operating mechanism within the casing from which the cover plate has been removed,

Fig. 3 is a transverse sectional view taken 60 on the line 3—3 of Fig. 2,

Fig. 4 is an enlarged detail sectional view showing the manner in which the latching mechanism is associated with a projection on the rotor structure for operating the signal 65 arm.

Fig. 5 is a plan view of the latching mechanism shown in Fig. 4, in which portions of the operating mechanism for the signal arm are shown in dotted lines.

Fig. 6 is an elevational view of the control switch.

Figs. 7 and 8 are end elevations and transverse section respectively of the switch mechanism, shown in Fig. 6.

Fig. 9 is an elevational view of the contact plate of the switch mechanism, shown in Fig. 8.

Fig. 10 is a wiring diagram showing the electrical connection between the several 80 parts of the invention.

Fig. 11 is a rear elevation of a motor vehicle showing the invention applied thereto in operative relation and illustrating in dotted lines the operative position of the signal 85 arm.

1 indicates a suitable mounting member which is formed of a single piece of material having a main base portion 2 from which projects a plurality of angularly arranged extensions 3, having the ends extended laterally as indicated at 4 in the same direction, and on which are suitably secured the stationary electro-magnets arranged in pairs 5 and 6. This mounting member has 95 the base portion 2 thereof formed with a plurality of laterally extending strip portions 7 arranged in parallel relation as shown in Figs. 2 and 3, and which are provided at the end portions with securing pieces 12 adapted to receive and have the bearing plates 13 removably secured thereto.

This bearing plate 13 and the base portion 2 of the member 1 are formed with aligned bearing openings for rotatably mounting the shaft 14 therein which is held against endwise movement by the structure including the pin 15 engaging the washer 16 at

one end of the bearing opening formed in the base portion 2, while the nut 17 engages the washer 18 for cooperation with the pin 15 and washer 16 to properly assemble the shaft for rotative movement in the device.

A rotary core member 19 is mounted on the shaft 14 in alinement with the pole pieces 20 of the pairs of electro-magnets 5 and 6 respectively, and this rotary armature 19 carries the electro-magnet 21 at opposite sides of the shaft 14, each one of which is adapted for magnetic cooperation with one of the pairs of electro-magnets 5 and 6 respectively.

This armature shaft 19 is suitably mounted on the rotary shaft 14 in alinement with the pole pieces 20 and serves to rotate shaft 14 upon energization of the electro-magnets 21 and either pair of magnets 5 or 6 respectively which are selectively energizable. One end of the armature 19 is provided with an anchor bar 22 to the end portions of which are secured operating springs 23 extending in opposite directions and in angular relation, having the free ends anchored to the rods 24 mounted in the base portion 2 as clearly illustrated in Fig. 2, and serve to normally hold the armature 19 in the operating coils therefor, in the position shown in Fig. 2 when the electro-magnets are not energized. This position is the normal position of the parts of the device in which the signalling arm 25 is in the positions shown in Figs. 1 and 11.

The opposite ends of the armature 19 from that mounting the angle bar 22 carries a depending projection 26 terminating in close proximity with the base portion 2 between a pair of latching elements generally indicated by the numerals 27 and 28. These latching elements 27 and 28 in the form as shown in the drawing are constructed of bell crank levers 29 pivotally mounted as indicated at 30 in Fig. 5 on the base portion 2 of member 1. One end of each of these bell crank levers carries an armature 31 which is associated with the pole pieces of the upper one of both pairs of electro-magnets 5 and 6 respectively, while the opposite end of each of these levers carries a block member 32 which is formed with an elongated slot 33. Each of the latch members 27 and 28 is pivotally mounted so that the block members 32 on the arms thereof are opposed to one another while suitable pins 34 mounted in the base portion 2, serve to limit the movement of these bell crank levers on their pivots 30, but permit sufficient movement in order to insure proper cooperation in this device.

The bell crank levers are normally operated in one direction so as to normally assume the position shown in Fig. 5 by the leaf spring 35 positioned between the pins 36 which are suitably secured in the base

portions 2 of the member 1. These blocks 32 on the ends of the bell crank levers normally lie in spaced relation and receive the pin or depending projection 26 on one end of the armature member 19 therebetween as shown in Fig. 5 in order that the signalling arm 25 will be held in the upright position.

From the above description, it will be understood that when the pair of electro-magnets 5 are energized, the latch member 28 will be moved on its pivot through the action of the magnetic field of the electro-magnet 5 on armature 31 which will move the block 32 downwardly and permit the depending pin 26 to move to the right as shown in Fig. 5 for permitting the operation of the signal arm 25 and the rotation of shaft 14. The corresponding parts for operation in an opposite direction are operated upon the energization of a pair of electro-magnets 6 so that the signal arm 25 can operate in the opposite direction in which the latch lever 27 permits its release for movement. The spring 23 will always return the signal arm to the position shown in Fig. 1 upon de-energization of the electro-magnet.

The mounting member 1 is suitably positioned within a casing 37 which is provided with suitable lugs 38 to permit its attachment to the motor vehicle as shown in Fig. 11 while a suitable cover plate 39 is removably mounted over the open end of the casing 37 in order to enclose the operative parts of the mechanism above described in the manner as shown in Fig. 3. The central portion of the cover 39 is provided with an opening which receives the shaft 14 so that the signalling arm 25 may be mounted on the shaft on the outside of the casing and the cover. The free end of the shaft 14 beyond the positions bounding the signal arm 25 which carries the lamp casing 40 in which is mounted a suitable illuminating means preferably electric lamps for illuminating the stop signal 41 and the tail light 42, while the arm 25 is provided with a lamp 43 which is illuminated by a suitable electric lamp the circuit for which will be described, hereinafter.

In Figs. 6 to 9 inclusive, I have inserted a special switch construction for controlling the operation of the signalling device above described, in which a suitable casing is illustrated at 44 provided with suitable means indicated at 45 for securing it to the steering wheels of a motor vehicle or at any other suitable point within reach of the driver, the casing 44 detachably receiving the cover 46. An insulating plate 47 is mounted within the casing 44 and is provided with a contact 48 which makes circuit with the disk 49 carried and operated by the switch handle 50. This disk 49 also carries a switch arm 130

51 of suitable resilient material which is adapted to make contact with any one of the contacts 52, 53 and 54.

The operating lever 50 is provided with a 5 suitable stop indicated at 55 in Fig. 6 in dotted lines and operates in a suitable slot in the cover 46 so as to limit the movement of the lever 50.

A suitable bracket 56 is mounted on the 10 cover 39 of the casing of the signal device and is adapted to suitably support a license plate thereon.

Referring particularly to Fig. 10, it 15 will be seen that the pair of electro-magnets 5 are interconnected in series by the wire 57 while one side of the circuit to the electro-magnet extends through the wire 58 to the lamp 59 mounted in signal arm 25 behind the lens 43 which in 20 turn is connected in circuit through the wire 60 to the terminal 54 on the plate 47. When the switch is in position for the resilient contact member 51 to engage the contact 54, the circuit is then closed to the contact 25 48 and through the wire 61 to the source of energy 62. The opposite side of the circuit from the source of energy extends through the wire 63 to the armature coils 21 and then 30 through the wire 64 to the other terminal of the pair of the electro-magnets 5, thus completing the circuit to the electro-magnet so that the armature coils 21 and the electro-magnets 5 upon being energized, will move the signal arm to the right hand position 35 shown in dotted lines in Fig. 11 for signalling a right turn of the motor vehicle equipped therewith. The lens 43 will also be illuminated so as to indicate this operation of the indicator at night.

40 The circuit for the left hand signalling position of the arm 25 extends from the source of energy 62 to the wire 61 to the switch and when the resilient contact 51 is engaged with the contact 52, the circuit is closed to the wire 65, lamp 66, and then through the wire 67 to one end of the pair of electro-magnets 6 which are connected in series to the wire 68. The circuit then leads from the electro-magnets 6 through the wire 50 69 to the coils 21 and back to the opposite terminals of the source of energy 62 through the wire 63. This will produce the proper operation so that the signal arm will be moved to the left hand dotted line position 55 shown in Fig. 11, for indicating a left turn, the lens 43 in the signal arm being illuminated by the lamp 66.

The switch is normally maintained with the resilient contact 51 in engagement with 60 the contact 53 on the insulating plate 47 as a

result of which the circuit from the source of energy 62 passes through the wire 61 and to the contact 53. A wire 70 is connected with the contact 53 and extends to the stop light 71 for illuminating the stop signal 41 the 65 circuit from which extends thru the wire 72 to a brake pedal control switch indicated generally at 73 from which the return circuit extends through the wire 74 to the opposite terminal of the source of energy 62. 70

It will thus be seen from this wiring circuit, that when the brake of the motor vehicle is operated to stop the vehicle, the proper signal will be given by the illumination of the stop signal 41 in the casing 40 75 through the energization of the lamp 71.

From the above description, it will therefore be clear that the invention provides a novel direction signal construction in which suitable electro-magnetic means serve to operate the indicating or signalling of arm as well as the latching means which is normally operative to retain the signalling arm in a predetermined position and prevent its oscillation due to jars or thrusts imparted to 85 it during the travel of the vehicle.

The special construction of the mounting member 1 with the bearing plate 13 permits the ready assembly of the operative parts of the construction so that the proper adjustment thereof may be made before mounting the same in the casing which will not change its adjusted operation. 90

Having thus described my invention, what I claim as new is:— 95

1. A mounting structure for electrically operated direction signals, comprising a plate member having a base portion formed with angularly arranged projections having the free ends terminating in lateral projections, a plurality of laterally projecting supporting strips being formed with and extending from said base portion in spaced parallel relation and means thereon for securing a bearing plate. 100 105

2. A mounting structure for electrically operated direction signals comprising a plate member having a base portion formed with angularly arranged projections with their free ends terminating in lateral projections, a plurality of laterally projecting supporting strips formed on and extending from said base portion in spaced parallel relation, means thereon for securing a bearing plate in spaced parallel relation from said base portion, said base portion and said plate providing bearing supports for rotatably mounting a signal shaft. 110 115

In testimony whereof I affix my signature.
HENRY H. HARADA.
